UNITED STATES PATENT OFFICE.

JOHN P. S. VOUGHT, OF DENVER, COLORADO.

FINGER-PRINT IDENTIFICATION-CARD AND METHOD OF PRODUCING SAME.

1,380,506.

Specification of Letters Patent. Patented June 7, 1921.

Application filed June 26, 1920. Serial No. 391,989.

To all whom it may concern:

Be it known that I, JOHN P. S. VOUGHT, a citizen of the United States, residing at the city and county of Denver and State 5 of Colorado, have invented certain new and useful Improvements in Finger-Print Identification-Cards and Methods of Producing Same; and I do declare the following to be a full, clear, and exact description 10 of the invention, such as will enable others skilled in the art to which it appertains to make and use the same, reference being had to the accompanying drawings and to the characters of reference marked 15 thereon, which form a part of this specification.

The object of this invention is to produce an identification card which will be unalterable, certain and positive in its identification of any special individual.

Briefly, the invention comprises a metallic plate which constitutes the card, and bears various identifying indicia. The card is provided with a space preferably counter- 25 sunk for the reception of the finger print, which space is surrounded by an arc of a circle described from a center adjacent the print space. The print is produced by means of a chemical applied to the finger, which at- 30 tacks the metal on the plate to produce a permanent print. Identifying lines are scratched in the metal through the print for the purpose of securing the print.

In the drawings:

35 Figure 1 is a face view of the card; and Fig. 2 is a section on the line 2-2 of Fig. 1.

A metal card 10 is provided with a countersunk or depressed portion 12, bounded by 40 the walls 14 to provide a print-receiving space as shown. A graduated arc 15 is described about the space 12 from a center at or adjacent the edge of the card, as indicated at 30, said center being also adjacent 45 the print space 12. The card is further provided with various indicia, such as would be used on an automobile license tag. For instance, at 16 there is a number indicating the State in which the license is issued; 50 at 18 the automobile license number; at 20 a series of numbers, any one of which can be marked to indicate a particular county; at 22 a space is outlined for the reception of the owner's signature; at 24 a counter- 55 sunk space 24 is provided for an attesting finger-print to be placed by the issuing offi-

cer. At 25 letters appear to indicate the finger from which the print P in space 12 is taken, "R. M." meaning right-middle.

The print P is produced by rubbing upon 60 the finger a chemical which will attack the metal of the plate, which is preferably zinc, to produce a permanent print. Validating lines V are then drawn from the point 30, as a center, by means of a stylus producing 65 corresponding scratches across the print. This will preferably be extended to cross the arc 15. These lines V determine one or more of the eight well-known patterns. For instance, one line passes through the loop 70 at L, and the other line through the delta at D. In addition to this a plurality of short guide lines G may be scratched into the metal to show other distinguishing features, such as dots and abrupt endings. 75

The lines V and G are scratched deeply into the plate so that it would be impossible to remove the print by any means known, and superpose another print wherein patterns and distinguishing marks would fall 80 in proper positions upon the various lines V and G.

From the foregoing it will be seen that it will be impossible to falsify a print, and in order to identify the bearer of the card 85 it will be merely necessary to take a print from the finger of the bearer indicated by the letters at 25, and compare said print with the original print P on the card. Thus it would be easy to determine whether the 90 bearer of an automobile license card such as shown in the drawing is the rightful owner of the machine which he drives.

In a similar manner, prints may be made for the use of banks, for policy holders in 95 life insurance companies, for personal use, and for infants and patients in hospitals. It is understood of course that prints may be taken from other parts of the body than fingers, such as the sole of the foot in the 100 case of an infant; and in the claims "finger-print" is to be construed as covering a print from any part of the body.

A chemical which will be used preferably is non-injurious to the skin, even though 105 not washed away, which renders this means of printing very desirable. Also, the marking of only one or two of the eight well-known patterns, and the marking of four or five other permanent distinctions, eliminates the necessity for considerable technical knowledge of the subject, and permits 110

of quickly comparing a print with the original print P of the card.

I claim:

1. The method of producing finger prints and the like comprising the application of a chemical which will attack a metal to the finger, and pressing the finger upon a sheet of metal subject to attack by said chemical whereby a print is produced.
- 10 2. In a method of producing finger prints, the step of obtaining a print from a finger by the application of a chemical on the finger to a sheet of metal subject to attack by the chemical to produce the print.
- 15 3. The method of producing an identifying finger print, comprising the application of a chemical to the finger, producing a print of the finger upon a sheet of metal subject to attack by the chemical, and scratching 20 lines in the sheet to mark prominent features of the print.
- 25 4. The method of producing an identifying finger print comprising the application of a chemical to the finger, pressing the finger upon a sheet of metal to produce the print, the chemical being adapted to attack the metal, scratching lines in the metal to mark the main features of the mark, said lines being drawn from a common center 30 located adjacent the print, and scratching other lines in the metal to mark other distinguishing features without regard to direction.
- 35 5. An identification card comprising a sheet of metal having identifying indicia thereon, a space for a finger print outlined on said sheet, and a graduated arc being delineated about said space having a center adjacent said space.
- 40 6. An identification card comprising a sheet of metal having identifying indicia thereon, a space for a finger print outlined on said sheet, and a graduated arc being delineated about said space having a center 45 adjacent said space, said space being countersunk below the level of the body of the plate to protect a print in the space.
7. An identification card comprising a sheet of metal having identifying indicia

thereon, a space for a finger print outlined 50 thereon, a graduated arc delineated about said space and having a center adjacent said space, a finger print in said space, and validating lines scratched in the metal to determine one of the well known patterns, said 55 lines passing through said center.

8. An identification card comprising a sheet of metal having identifying indicia thereon, a space for a finger print outlined 60 thereon, a graduated arc delineated about said space and having a center adjacent said space, a finger print in said space, validating lines scratched in the metal to determine one of the well known patterns, said lines passing through said center, and guide lines 65 leading from other distinguishing features.

9. An identification card comprising a sheet of metal having identifying indicia thereon, a space for a finger print outlined 70 thereon, a graduated arc delineated about said space and having a center adjacent said space, a finger print in said space, validating lines scratched in the metal to determine one of the well known patterns, said lines passing through said center, and guide lines 75 leading from other distinguishing features, said space being countersunk below the level of the body of the plate to protect the print.

10. An identification card comprising a sheet of metal having identifying indicia 80 thereon, a space for a finger print outlined thereon, a graduated arc delineated about said space and having a center adjacent said space, a finger print in said space, validating lines scratched in the metal to determine 85 one of the well known patterns, said lines passing through said center, guide lines leading from other distinguishing features, said space being countersunk below the level of the body of the plate to protect the print. 90

In testimony whereof I affix my signature.

JOHN P. S. VOGHT.
